US0D1077102S

(12) **United States Design Patent** (10) Patent No.: **US D1,077,102 S**
(45) Date of Patent: ** May 27, 2025

(54) **GOLF CLUB HEAD**

(71) Applicant: **KARSTEN MANUFACTURING CORPORATION**, Phoenix, AZ (US)

(72) Inventors: **Joshua A. Degerness**, Scottsdale, AZ (US); **Ryan H. Davis**, Phoenix, AZ (US)

(73) Assignee: **Karsten Manufacturing Corporation**, Phoenix, AZ (US)

(**) Term: **15 Years**

(21) Appl. No.: **29/879,593**

(22) Filed: **Jul. 10, 2023**

(51) LOC (15) Cl. **21-02**

(52) U.S. Cl.

USPC **D21/747**

Primary Examiner — Mitchell I. Siegel

(57) **CLAIM**

The ornamental design for a golf club head as shown and described.

DESCRIPTION

FIG. 1 is a top perspective view of a golf club head;
FIG. 2 is a bottom perspective view of the golf club head of FIG. 1;
FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1; and,
FIG. 8 is a toe side view of the golf club head of FIG. 1.
The broken lines shown on the drawings form no part of the claimed design.

1 Claim, 7 Drawing Sheets
